CHAIR BASE

Otto Schachtel, Chicago, Ill., assignor to Theo. A. Kochs Company, Chicago, Ill., a corporation of Illinois

Application March 9, 1935, Serial No. 10,258

10 Claims. (Cl. 155—138)

The chair base of the present invention is intended primarily for use as a support for the seat of a swivel chair, which may be a barber chair, a dental chair, a beauty parlor chair, or any other type of swivel chair, and the base is adapted for numerous uses in which a firm, rigid, easily assembled base of attractive appearance and strong and unyielding structure is desired.

The base of the present invention moreover is one in which the parts can be made in quantity and readily assembled, and which lends itself to the requirements of modernistic design, and in which furthermore a bright metallic finish may be imparted without marring or disfigurement from screws, rivet heads, or other agencies employed in the assembling of the parts.

Further objects and details of the invention will appear from the description thereof in conjunction with the accompanying drawing, wherein,—

20 Figure 1 is a perspective view of a chair for use in a beauty parlor, embodying the base of the present invention;

Fig. 2 is an enlarged sectional detail of the center post with the legs radiating therefrom;

25 Fig. 3 is a perspective view looking into the upper end of one of the legs;

Fig. 4 is a similar view looking into the lower end of one of the legs; and

Fig. 5 is a perspective view of the coupling for 30 securing the legs within the center post.

The base or support comprises a center post 10 which is provided with threads 11 throughout its medial region, which threads engage with the exterior threads 12 of a standard 13 which carries 35 the chair seat 14.

The center post 10 is supported by a plurality of U-shaped legs 15, each of which has its upper and lower ends secured to the center post, and each of which is provided at or near the bend or loop 40 of the leg with a foot 16 which rests upon the floor, holding the legs with the post in elevated relation with respect to the surface of the floor.

Each of the U-shaped legs is constructed of tubing which is flattened on the sides to afford an 45 oval or elliptical cross section, and the upper and lower inturned ends of each of the legs are concaved to fit snugly against the exterior surface of the center post at the point of attachment for the end of the leg. The upper end 17 is also cut 50 obliquely with respect to the center axis of the leg, so that the upper end of the leg will extend downwardly and outwardly from the center post and make a firm and closely fitting connection therewith at its inner end. The lower end 18 of 55 the leg extends radially outward and thereafter

dips slightly downward toward the outer bend 19, at which point the foot 16 is secured.

Each of the legs at its lower end 18 has inserted thereinto a pin 20 which lies upon the base of the lower end of the leg and is secured thereto by a spot weld 21 formed on the under side of the leg and at a point which will be practically indiscernible when the base is finished.

The pins 20 project inwardly through apertures 22 near the lower end of the post 10, and the inner ends of the pins are entered through apertures 23 in a coupling plug 24 located centrally within the post 10 near the lower end thereof. The pins are united to the center coupling plug by spot welds 25.

15 The upper end 17 of each leg has entered thereinto a nut 26 which is secured by a spot welding 27 in right angle relation to the axis of this portion of the leg, and the nut is threaded to receive a screw 28 which is entered through an obliquely disposed bore 29 in the center post near the upper end thereof, which bore is countersunk at its inner end to receive the head of the screw and is located in such relation to the upper end on the post as to permit a screw driver to be manipulated 20 through the upper end of the post in order to draw the upper end of each leg into close abutment 25 with the center post.

The base constructed as above described will afford a strong and rigid support for a chair or 30 the like. By uniting the inwardly projecting pins 20 at the lower ends of the respective U-shaped legs in the manner shown, a strong, rigid and unyielding connection will be afforded and vertical thrusts will be adequately resisted.

35 In short, the coupling furnishes a bridge between the lower ends of the legs, and the post 10 is supported medially upon said bridge in such a way as to maintain a tight fit at all times between the center post and the legs radiating 40 therefrom. This is due to the fact that a downward thrust exerted against the inwardly projecting ends of the pins 20 will result in an inward thrust causing a cramping or binding of the inner faces of the lower ends of the legs 45 against the outer surface of the center post, so that a tight, firm joint will at all times be maintained. In view of the fact that the upper ends of the legs are under thrust inwardly against the center post and are not subjected in like degree to a downward thrust, a cross connection like the coupling 24 is unnecessary, which leaves the center of the post unobstructed for the travel of the standard 13 which supports the chair seat.

50 All of the connections, with the exception of 55

the spot welds 21, are completely hidden, and the welds 21 practically so, so that the center post and legs may be given a bright metallic finish, such as a chromium finish, in keeping 5 with modernistic designs in furniture, and at the same time the structure is one which permits of variation in the finish and configuration of the U-shaped legs without variation in general structure or the means provided for affording the 10 connections.

Although the invention has been described with particularity as to detail, it is not the intention, unless otherwise indicated, to limit the invention to the particular structure shown, 15 since modifications may be made therein without departing from the principles of the invention.

I claim:

1. In a base of the class described, the combination of a center post, radially extending legs of looped formation each having an upper end and a lower end in spaced radially abutting relation to the center post, connecting means extending from the lower ends of said legs and through transversely the interior of the post for affording a bridge connection between the lower ends of said legs, and means for securing the upper ends of the legs to the post.

2. In a base of the class described, the combination of a center post, radially extending legs of looped formation each having an upper end and a lower end in spaced radially abutting relation to the center post, connecting means extending from the lower ends of said legs and through transversely the interior of the post for affording a bridge connection between the lower ends of said legs, a nut carried by the upper end of each of said legs, and a screw entered through the contiguous wall of the post and into the associated nut.

3. In a base of the class described, the combination of a center post, radially extending legs of looped formation each having an upper end and a lower end in spaced abutting relation to the center post, connecting means extending from the lower ends of said legs and through the interior of the post for affording a bridge connection between the lower ends of said legs, a nut carried by the upper end of each of said legs, and a screw entered through the contiguous wall of the post and into the associated nut at an oblique angle near the top of the post and in position to permit manipulation of the screw by a screw driver from a position above the post.

4. In a base of the class described, the combination of a tubular center post, a plurality of radially extending tubular legs each of looped formation affording upper and lower ends in spaced abutting relation to the center post, pins inwardly extending from the lower ends of the respective legs and into the interior of the post, a coupling member engaging said pins and affording a bridge connection between the legs, and means for securing the upper ends of the legs to the center post.

5. In a base of the class described, the combination of a tubular center post, a plurality of radially extending tubular legs each of looped formation affording upper and lower ends in spaced abutting relation to the center post, pins inwardly extending from the lower ends of the respective legs and into the interior of the post, a coupling member engaging said pins and affording a bridge connection between the legs, a screw for each of the upper ends of the legs, said

screws extending obliquely through the contiguous wall of the post, and means within each of said leg ends into which the associated screw is threaded.

6. In a base of the class described, the combination of a tubular center post, a plurality of radially extending tubular legs each of looped formation affording upper and lower ends in spaced abutting relation to the center post, pins inwardly extending from the lower ends of the respective legs and into the interior of the post, a coupling member engaging said pins and affording a bridge connection between the legs, a screw for each of the upper ends of the legs, said screws extending obliquely through the continuous wall of the post, and means within each of said ends into which the associated screw is threaded, the respective screws being located near the upper end of the tubular post and in position to permit manipulation of each screw 20 by a screw driver from a position above the upper end of said post.

7. In a base of the class described, the combination of a tubular center post, a plurality of radially extending tubular legs each looped to afford upper and lower ends in spaced abutting relation to the center post, pins extending inwardly through the center post from the lower ends of the respective legs, said pins being rigidly secured to the respective legs, a coupling plug within the center post into which the inner ends of the pins are inserted and rigidly secured to afford a bridge connection for the lower ends of the legs, and means for holding the upper ends of the legs in abutting relation to the center post.

8. In a base of the class described, the combination of a tubular center post, a plurality of radially extending tubular legs each looped to afford upper and lower ends in spaced abutting relation to the center post, pins extending inwardly through the center post from the lower ends of the respective legs, said pins being rigidly secured to the respective legs, a coupling plug within the center post into which the inner ends of the pins are inserted and rigidly secured to afford a bridge connection for the lower ends of the legs, and screw means for securing the upper ends of the respective legs to the center post.

9. In a base of the class described, the combination of a tubular post, a plurality of radially extending legs each of tubing looped to afford upper and lower ends in spaced abutting relation to the center post, pins extending inwardly through the center post from the lower ends of the respective legs, said pins being rigidly secured to the respective legs, a coupling plug within the center post into which the inner ends of the pins are inserted and rigidly secured to afford a bridge connection for the lower ends of the legs, a screw for each of the upper leg ends entered obliquely through the wall of the center post and into the interior of the leg ends and a member rigid with each leg end for receiving said screw to permit each leg end to be drawn into abutting relation to the center post.

10. In a base of the class described, the combination of a tubular post, a plurality of radially extending legs each of tubing looped to afford upper and lower ends in spaced abutting relation to the center post, pins extending inwardly through the center post from the lower ends of the respective legs, said pins being rigidly secured to the respective legs, a coupling plug

within the center post into which the inner ends of the pins are inserted and rigidly secured to afford a bridge connection for the lower ends of the legs, a screw for each of the upper leg ends entered obliquely through the wall of the center post and into the interior of the leg ends and a member rigid with each leg end for receiving

said screw to permit each leg end to be drawn into abutting relation to the center post, the screws being located in close proximity to the upper end of the post and in position to permit manipulation thereof by a screw driver from 5 a point beyond the upper end of the post.

OTTO SCHACHTEL.
